REFRACTORY BLOCK

Horace N. Hall, Collegeville, Pa., assignor to E. J. Lavino and Company, Philadelphia, Pa., a corporation of Delaware

Filed Aug. 1, 1961, Ser. No. 66,155

Term of patent 14 years

(Cl. D81—25)

Fig. 1.

Fig. 2.

Fig. 3.

Fig. 4.

FIG. 1 is a top perspective view of a refractory block showing my new design;

FIG. 2 is a top perspective view of the refractory block showing the other sides of the block;

FIG. 3 is a bottom plan view of said block on an enlarged scale; and

FIG. 4 is a partial sectional view taken on lines 4—4 of FIG. 1 on an enlarged scale.

I claim:

The ornamental design for a refractory block, as shown.
